UNITED STATES PATENT OFFICE.

GEORGE A. MILLAR, OF ENSLEY, ALABAMA.

AIR-CUSHION NOZZLE.

1,389,593.

Specification of Letters Patent. Patented Sept. 6, 1921.

Application filed March 5, 1920. Serial No. 363,483.

To all whom it may concern:

Be it known that I, GEORGE A. MILLAR, a citizen of the United States, residing at Ensley, in the county of Jefferson and State 5 of Alabama, have invented certain new and useful Improvements in Air-Cushion Nozzles; and I do hereby declare the following to be a full, clear, and exact description of the invention such as will enable others 10 skilled in the art to which it appertains to make and use the same.

The present invention relates to hose nozzles, and aims to provide a novel and improved nozzle adapted especially for use on 15 fire hose or fire extinguishers in order to increase the velocity of the stream and distance to which it is thrown, by the elimination of adverse action of the air, at the tip of the nozzle as well as rendering the 20 stream smooth and noiseless.

Another object is the provision of a rim surrounding the tip of the nozzle to serve as a protection for insuring a perfect end or tip on the nozzle at all times, protecting 25 the end of the nozzle from being injured if it strikes or drops on a hard surface.

A further object is the provision of means for the entrance of air from in rear of the tip of the nozzle to provide an air cushion 30 surrounding the stream where it leaves the nozzle, and serving the purposes of increasing the velocity and smoothness of the stream and the distance to which it is thrown, as well as avoiding the usual action 35 of the air in breaking up the stream, to a large extent.

With the foregoing and other objects in view, which will be apparent as the description proceeds, the invention resides in 40 the construction and arrangement of parts hereinafter described and claimed, it being understood that changes can be made within the scope of what is claimed without departing from the spirit of the invention.

45 The invention is illustrated in the accompanying drawing, wherein:

Figure 1 is a longitudinal section of the improved nozzle.

Fig. 2 is an end view thereof.

50 The nozzle 4 can be made in any suitable size, having an attaching portion 5 at its larger end, and the passage of the nozzle tapers to a point 6 near the tip from which

point the passage is substantially cylindrical or uniform in diameter to the tip or 55 discharge end.

In carrying out the invention, the nozzle is formed, with an annular outstanding flange 7, which is spaced rearwardly slightly from the discharge end of the nozzle, and 60 said flange has a forwardly-extending cylindrical rim 8 projecting for a distance beyond the tip of the nozzle and of a larger diameter than the tip. The outer end of 65 the rim 8 has an outstanding annular rib or bead 9, which, in contacting with a hard surface, should the nozzle be dropped or strike such surface, will prevent the tip of the nozzle being injured. In this way, the discharge end of the nozzle will remain 70 perfect and the stream passes through the rim with an annular air space between said rim and stream.

The flange 7 has an annular series of apertures 10 therein substantially parallel with 75 the rim 8 for admitting air from in rear of the discharge end of the nozzle within the rim 8, so that the stream of water or liquid will draw air through the apertures 10, forming an air cushion between the rim and stream, whereby to smoothen the stream and increase the velocity thereof, as well as avoiding noise and agitation of the stream. The air will continue to flow through the apertures 10 due to the action of the stream 80 in drawing the air into the rim 8, which has been found to materially increase the velocity of the stream and the distance to which it is thrown, as well as making the 85 stream smooth and noiseless.

Having thus described the invention, what is claimed as new is:

A nozzle having an outstanding annular flange slightly in rear of the tip thereof, and a cylindrical rim carried by said flange 95 surrounding and projecting beyond said tip, said flange having air inlet openings substantially parallel with said rim.

In testimony whereof I have signed my name to this specification in the presence of 100 two subscribing witnesses.

GEORGE A. MILLAR.
